UNITED STATES PATENT OFFICE.

WARNER B. COOKE OF JENKINTOWN, PENNSYLVANIA, ASSIGNOR TO WILLIAM WHARTON, JR., & COMPANY INCORPORATED, OF PHILADELPHIA, PENNSYLVANIA, A CORPORATION OF PENNSYLVANIA.

MOVABLE-POINT CROSSING.

No. 864,717.

Specification of Letters Patent.

Patented April 14, 1908.

Application filed April 26, 1907. Serial No. 370,518.

To all whom it may concern:

Be it known that I, WARNER B. COOKE, a citizen of the United States, residing in Jenkintown, Pennsylvania, have invented certain Improvements in Movable-Point Crossings, of which the following is a specification.

My invention relates to that type of railway crossings in which movable point rails are used so that each track when the points are set will be unbroken.

The object of my present invention is to provide the point rails with a hard metal point of special construction which will be more substantial than the ordinary points used and which can be firmly secured to the point rails.

In the accompanying drawings: Figure 1, is a plan view of a crossing illustrating my invention; Fig. 2, is an enlarged plan view 20 of a portion of the crossing illustrated in Fig. 1; Fig. 3, is a transverse sectional view on the line 3—3, Fig. 2; Fig. 4, is a transverse sectional view on the line 4—4, Fig. 2; and Figs. 5, 6 and 7, are perspective views illustrating details of the invention.

A—A are stock rails, which are formed to produce the "knuckle" illustrated in the drawings and which may be made as illustrated in Fig. 1, and claimed in Patent No. 30 812,794, granted Feb. 13, 1906, to Frank L. Keim, for a movable point railway crossing, or in accordance with my Patent 819,520, May 1, 1906, though if desired, they may be plain rails bent to form the knuckle.

B, B are the movable point rails terminating, in the present instance, some distance from the knuckle on each side and connected together by tie rods b, b', the rods b, b extend beyond the stock rails. These rods may be 40 coupled to switch operating mechanism in any manner desired. Usually such operating mechanism extends from an interlocking tower and the rails are so coupled that they will work in unison, one pair moving to one 45 side of the structure, while the other pair is shifted to the opposite side, giving a clear, unbroken track for the wheels of a car passing over the crossing.

In Fig. 1, the movable points are so shifted 50 that the track A' is unbroken, while the track A' is broken. The point rails B, in the present instance, have hard metal points D, shown in detail in Figs. 2, 3 and 4, preferably made of manganese steel. Each point has 55 an extension d against which rests the rail B,

and this extension is preferably situated on that side of the rail adjoining the stock rail A, the end of such extension being beveled at d' so that the false flange on the outer side of the guttered wheel will ride upon the inclined portion onto the surface of the point D. The point section has a flange base d" on one side alining with the base flange of the rail and the side of the point section is recessed so as to coincide with the shape of the rail, 65 preferably extending the full length of the point section and along a portion of the point rail B.

E is a strap extending along the side of the point section and fitting snugly in the space 70 between the base flange and the head of the rail, bolts being used, as shown in Figs. 3 and 4, to firmly fasten these strap pieces to the point section and the point rail, of which some pass through the rail and the rear extension of the point section, as illustrated 75 in Fig. 4, making a very rigid construction.

The tie rods b—b' are secured to brackets b" attached to the point sections and rails B, as indicated in Fig. 1, although these rods may 80 be attached to the movable point rails in any suitable manner.

By making the point portion of the rails of hard metal the breaking down of the point under the hammer blows of passing wheels 85 is avoided, and by providing the rear extension with the beveled portion on the outer side of the point rails it allows the false flange of a guttered wheel to rise up the inclined portion on to the extension of the 90 head so as to be lifted to the plane of the head of the track rails over which it will pass without wearing a groove therein as would otherwise be the case. Further this construction affords means for a secure attachment of the point to the rail.

I claim:

1. In a movable point crossing, the combination, with the knuckle-forming track rail, of the movable point rails, terminating some distance on each side of the "knuckle", 100 the hard metal point-forming piece, whose upper surface is in the same plane as the said point rail, said point-forming piece having the rearward extension adjacent the outer edge of the head of the point rail, together with means for securing said point rail and hard metal point-forming piece together, substantially as described.

2. In a movable point crossing, the com- 110

bination, with the knuckle-forming track rail, of the movable point-rails terminating some distance on each side of the "knuckle", the hard metal point-forming piece whose 5 upper surface is in the same plane as the said point rail, said point-forming piece having the rearward extension adjacent the outer edge of the head of the point rail, and whose free rear end is downwardly beveled, 10 together with means for securing said point rail and hard metal point-forming piece together, substantially as described.

3. In a movable point crossing, the combination, with the knuckle-forming track rail, of the movable point rails, terminating some distance on each side of the "knuckle", the hard metal point-forming piece, whose 15 upper surface is in the same plane as the

said point rail, said point-forming piece having the rearward extension adjacent the 20 outer edge of the head of the point rail, and having also a web portion, together with the strap piece extending the length of the point-forming piece, its forward portion lying against the web of the latter, and its rear 25 portion against the web of the point rail, together with the bolts securing said point-forming piece, point rails, and strap, together, substantially as described.

In testimony whereof, I have signed my 30 name to this specification, in the presence of two subscribing witnesses.

WARNER B. COOKE.
